UNITED STATES PATENT OFFICE.

CHARLES CHEVALLIER, OF LONDON, ENGLAND.

DEVICE FOR REPEATING ON THE ENGINE THE SIGNALS GIVEN ON THE LINE.

1,230,671.

Specification of Letters Patent. Patented June 19, 1917.

Application filed August 26, 1914. Serial No. 858,779.

To all whom it may concern:

Be it known that I, CHARLES CHEVALLIER, a citizen of the Republic of France, residing at 1 Rutland street, Regent, London, N. W., England, have invented a new and useful 5 Device for Repeating on the Engine the Signals Given on the Line, of which the following is a specification.

This invention relates to a device for repeating on the engine the signals given on the line. The signals are repeated in front of the engineer and of the stoker who thus are immediately informed of the position occupied by the semaphore, the round disk 10 or the square disk, whatever may be the weather, however badly the disk may be lighted, and for whatever reason the signal itself could not be seen by the engineer. This device has the advantage that it does 15 not require any alteration in the lining or any transformation of the signals. The apparatus does not comprise a signal whistle which is a further advantage, since with an ordinary whistle the engineer relies too 20 much on it and consequently neglects to watch the signals.

The device consists of two windows, a white one and a red one mounted on the wind screen of the engine. The windows 30 are uncovered according to the position of the signals. If the line is blocked the red window is uncovered and the white is covered and inversely if the line is clear.

The device for obturating the windows is 35 controlled by compressed air sent out by rubber balls which are compressed by rods influenced by an oscillating lever mounted under the engine. This lever is operated by a trip device situated between the rails and 40 arranged at least 200 meters in rear of the signal from which it is operated itself.

A lantern is mounted on the line to indicate the place where the apparatus is 45 mounted so that, if the signals are not visible the engine driver knows where they are.

In the accompanying drawings the invention is shown by way of example:

Figure 1 is a perspective view of a line 50 with trip devices for repeating the signals on the engine.

Fig. 2 is a cross section of Fig. 1 the trip device being in the position which it assumes when the line is free or clear.

Fig. 3 is a similar view which shows the

device in the position which it assumes 55 when the line is blocked.

Fig. 4 is a section on line 4—4 of Fig. 1.

Fig. 5 is a front view of the wind screen with the red and white windows.

Fig. 6 shows the apparatus operating one 60 of the obturators.

Between the rails 1, 2 a trip device 3 is arranged adapted to pivot around an axle 4. This trip device 3 is lifted by means of two connecting rods 5, 6. The connecting rod 6 65 is fixed on a shaft 7 which is mounted in bearings and is operated by the same apparatus which operates the signal to be repeated. On this shaft a lever 8 is fixed which has a counterweight 9 maintaining 70 the lever in determined positions. This trip device 3 is preferably situated at the right of the line and it is provided alone if only the signals of the semaphore are to be repeated, but if also the signals of the round 75 or square disk are to be repeated, which indicate slacken speed or stop respectively, two trip devices are arranged, one at the right and the other at the left of the line. The second device is of similar construction 80 to the first one and it further has an abutment 10, articulated at an axle 11 adapted to be maintained in lifted position by two connecting rods 12, 13, the connecting rod 13 being fixed on the shaft 7. If there are 85 two trip devices, the one is in the raised or lifted position while the other one is in the lowered position and inversely, said positions corresponding with the positions of the signals.

The device on the engine designed to come 90 in contact with the trip devices 3, 10 consists of the lever 16 pivotally mounted on an axle 17 which is fixed in a support 18 under the engine. The lever 16 is preferably provided 95 with inclined surfaces 14, 15 at the end, the incline corresponding with the slope of the abutments 3 and 10 to serve for softening or decreasing the shock when the lever comes in contact with the trip devices. The ends of 100 the lever 16 carry rods 19, 19^a with large heads 20. Above the heads 20 rubber balls 21 are mounted which are connected by hose or conduits 22 with the obturating devices for the white window 23 and red window 24.

The rods 19, 19^a (see Fig. 6) are located 105 in tubular sliding pieces or guide tubes 25 in which said rods can move, the movement of

the rods being braked by means of blade springs 26 which bear against the inner wall of said tube 25. The blade springs prevent the accidental displacement of the rod.

- 5 The device for showing the signals in the cab is shown in Fig. 5 and comprises a lamp 27 located in a box 28 provided with a white window 23 and a red window 24. Arranged to slide between the lamp burner and the windows is a door or obturator 30 large enough to cover either of the windows while uncovering the other. At the lower end of the door are fixed impact blocks 32 for moving the door. Fixed to the box 28 are cylinders 33 with which the hose connections 22 are in communication and these cylinders are provided with plungers 34 which are operated by the air which is compressed by the action of the rods 19, 19^a on their corresponding balls 21, (see Figs. 2 and 6) and are thus caused to strike against the blocks 32, driving the door 30 from its position closing one window to the opposite end closing the other window.
- 25 When the semaphore is operated, the lever 8 is actuated upon at the same time by means of a device similar to the tongue of a switch whereby the shaft 7 is rotated and consequently the connecting rod 6, fixed on said shaft is actuated. In moving, the connecting rod 6 assumes an almost vertical position and draws along the connecting rod 5 whereby the trip device is lifted. If now an engine which is fitted with the device hereinbefore described moves over the trip device, the inclined surface 14 which is in its lower position, strikes against the trip device 3 which is lifted, so that the lever 16 swings around the axle 17 and lifts the rod 19, the head 20 of which compresses the rubber ball 21. The air forced out of the rubber ball operates the obturator which uncovers the red window 24 and covers the white window 23. The engine driver can thus see at once that the line is blocked and has time enough to observe the semaphore before the engine arrives at the signal so that the speed of the engine can be reduced and if the line is still blocked when the engine arrives at the round disk the inclined surface will still be lifted and consequently the red window will be still uncovered. The engine can slowly continue until it arrives at the square disk where it will stop. If, however, the square disk is in the open position the trip device 3 of this disk is lowered and the trip device 10 lifted so that the inclined surface 15 will come in contact with the trip 10 so that the lever 16 swings and the obturator is operated so that it covers the red window and uncovers the white window, the line being free the engine driver can continue at full speed.

Claims:

- 65 1. In a device for repeating on the engine

the signals given on the line, the combination comprising trip devices on the line, a lantern having a plurality of windows and located on the engine, an obturator for said windows, and means actuated by contact with said trip devices for operating said obturator.

2. In a device for repeating on the engine the signals given on the line, the combination comprising trip devices on the line, a lantern located on the engine and provided with a white window and a red window, an obturator slidably mounted to close one or the other of said windows, and means actuated by contact with said trip devices for operating said obturator.

3. In a device for repeating on the engine the signals given on the line, the combination comprising trip devices on the line, a lantern located on the engine and provided with a white window and a red window, an obturator slidably mounted to close one or the other of said windows, plungers arranged to operate said obturator, cylinders in which said plungers are disposed, flexible air containers in communication with said cylinders, and means operated by the said trip devices to compress said containers.

4. In a device for repeating on the engine the signals given on the line, the combination comprising trip devices on the line, indicating apparatus on the engine, plungers arranged to operate said apparatus, cylinders in which said plungers are disposed, flexible air containers in communication with said cylinders and means operated by the said trip devices to compress said containers.

5. In a device for repeating on the engine the signals given on the line, the combination comprising trip devices on the line, indicating apparatus on the engine, plungers arranged to operate said apparatus, cylinders in which said plungers are disposed, flexible air containers in communication with said cylinders, and rods provided with heads adapted to compress said containers and arranged to be operated by the said trip devices.

6. In a device for repeating on the engine the signals given on the line, the combination comprising trip devices on the line, a lantern located on the engine and provided with a pair of windows, an obturator for closing one or other of said windows, and means actuated by said trip devices for moving said obturator from one of its operative positions to the other.

7. In a device for repeating on the engine the signals given on the line, the combination comprising trip devices on the line, a lantern located on the engine and provided with a pair of windows, an obturator for closing one or the other of said windows, plungers arranged to operate said obturator,

cylinders in which said plungers are disposed, flexible air containers in communication with said cylinders, and means operated by the said trip devices to compress said containers.

5 8. In a device for repeating on the engine the signals given on the line, the combination comprising a trip member pivoted at one end to the track, a shaft disposed transversely of the track, an arm projecting from said shaft and keyed thereto, a link connecting said arm with the free end of said trip member, a second trip member arranged to be similarly operated by said shaft so as to 10 be inoperative position when the first trip member is in operative position and vice versa, means to rotate said shaft, and signal indicating means carried by the engine and arranged to be actuated by the said trip 15 members.

20 9. A device for repeating on the engine or train, signals given on the line, comprising trip devices on the line movable between the track rails, a shaft operatively connected 25 with the signal devices, connecting rods be-

tween said shaft and the trip devices for raising and lowering the latter, a lever having a counterweight for maintaining said shaft in determined positions, said trip devices being so located that one of said trip 30 devices is lifted while the other of said devices is lowered and vice versa, a white and a red window arranged in the wind screen of the engine, an obturator adapted to alternately cover and uncover said windows, 35 compressible air containing members mounted upon the train, a pivoted member also carried by the train and having inclined portions for abutment with said trip devices and having rod portions with heads to engage and compress alternately the air containing members for operating the obturator correspondingly with the signals on the line to show a similar signal on the train.

40 In testimony whereof I affix my signature 45 in presence of two witnesses.
